JAMES E. MACKIE AND AARON J. SMITH, OF LONG BEACH, CALIFORNIA

FLOOR SLEEPER

Application filed March 3, 1930. Serial No. 432,732.

This invention relates to a floor sleeper, screed and furring strip which is adapted to be positioned in a concrete floor or in a wall. When in position, the sleeper affords a means 5 for securing flooring and the like over a concrete base, or to secure wall covering or trimming when used as a furring strip.

An object of our invention is to provide a sleeper of the character stated which can 10 be quickly and easily placed in position in the floor or wall, and when placed in the floor will materially reduce the over-all height of a building.

Another object is to provide a sleeper 15 which can also be effectively used as a screed for the concrete or cement floor.

An advantage of our sleeper is that it may be installed in multiples, thus materially decreasing the time necessary to install the 20 sleepers.

Another advantage of our sleeper is that it is securely anchored in the concrete.

Other objects, advantages and features of invention may appear from the accompanying drawing, the subjoined detailed description, and the appended claims.

In the drawing

Figure 1 is a transverse sectional view of a pair of sleepers in operative position, and 30 with the flooring secured thereto.

Figure 2 is a transverse sectional view of a slightly modified form of sleeper.

Figure 3 is a side elevation of one of the sleepers.

Figure 4 is a plan view of a plurality of sleepers secured to master strips prior to installing.

Referring more particularly to the drawing, the numeral 1 indicates a metal case, 40 preferably formed of a comparatively light sheet metal which can be readily stamped into the shape desired. The case is formed into a substantially rectangular trough 2 in which a wooden strip 3 is placed. The strip 45 3 is preferably creosoted so as to materially lengthen its effective life. At the upper end, the case 1 is bent outwardly into flanges 4-4, and these flanges are bent downwardly at their outer ends to form spacing ribs 5. As 50 shown in Figures 1 and 2, the concrete floor

comes to the level of the lower edge of the spacing ribs 5, and these ribs thus provide a screed to level off the concrete floor, as will be described in detail later.

To securely anchor the case 1 into the concrete floor or wall 6, we provide at the lower edge of the case longitudinally extending anchor ribs 7. The anchor ribs are integrally formed with the metal case, and as will be evident, provide an effective means against 55 removal or displacement of the sleeper. The flooring or the like 8 is placed over the sleepers and nails 9 are driven through the flooring into the wooden strip 3 and the nails as they come in contact with the bottom of the 60 case 1, will be clinched over as shown in Figures 1 and 2.

To hold the wooden strip 3 securely in the case 1, we provide a plurality of ears 10 which are cut out of the sides of the case, and 65 are driven inwardly into the wooden strip, thus securely holding it against displacement.

Our sleepers may be positioned in the following manner: A plurality of the sleepers 70 are secured to master strips 11-11 by means of nails which extend through the flanges 4. The master strips and the attached sleepers are leveled by any suitable and well-known means, after which the concrete flooring is 75 poured. The ribs 5 act as a screed to gage the top surface of the floor.

A slightly modified form of sleeper is shown in Figure 2. The metal case 12 is 80 stamped into the shape of a truncated prism in cross section, and the wooden strip 13 conforms in shape to the metal case. By this means the wooden strip is securely held in position without requiring the cutout ears 85 as previously described. Outwardly extending flanges 14-14 are provided at the upper end of the case, and these flanges are turned 90 downwardly into spacing ribs 15 which are identical in construction to the flanges 4 and ribs 5.

Having described our invention, we claim:

1. A sleeper or strip comprising an elongated metal case, said case being formed in the nature of a trough, a wooden strip 100

secured in the case and depending ribs at the upper end of said case.

5 2. A sleeper and strip comprising a metal case formed into an elongated trough, a wooden strip positioned in the trough, outwardly extending flanges at the upper end of the case, said flanges being bent downwardly into depending ribs.

10 3. A sleeper or strip comprising an elongated metal case, said case being formed in the nature of a trough, a wooden strip secured in the case and depending ribs at the upper end of said case, and anchor ribs extending longitudinally of the case adjacent the lower end thereof.

15 4. A sleeper and strip comprising a metal case formed into an elongated trough, a wooden strip positioned in the trough, outwardly extending flanges at the upper end of the case, said flanges being bent downwardly into depending ribs, and anchor ribs extending longitudinally of the case adjacent the lower end thereof.

20 5. A sleeper and strip comprising a metal case formed into an elongated trough, a wooden strip in said trough, a plurality of ears cut from the case and driven inwardly into the wooden strip, a pair of outwardly extending flanges formed on the upper end of the case, said flanges being bent downwardly at the outer ends thereof to form depending ribs.

25 6. A sleeper and strip comprising a metal case formed into an elongated trough, a wooden strip in said trough, a plurality of ears cut from the case and driven inwardly into the wooden strip, a pair of outwardly extending flanges formed on the upper end of the case, said flanges being bent downwardly at the outer ends thereof to form depending ribs, and longitudinally extending anchor ribs adjacent the lower end of the case.

30 In testimony whereof, we affix our signatures.

35 JAMES E. MACKIE.
AARON J. SMITH.
